KNITTING BALL CARRIER OR SIMILAR ARTICLE

Herbert L. J. Partridge, New York, N. Y.

Application June 28, 1954, Serial No. 31,203

Term of patent 14 years

(Cl. D3—19)

FIG. 1.

FIG. 2.

To all whom it may concern:

Be it known that I, Herbert L. J. Partridge, a citizen of the United States, residing at New York city, New York, have invented a new, original, and ornamental Design for a Knitting Ball Carrier or Similar Article, of which the following is a specification, reference being had to the accompanying drawings, forming a part hereof.

Fig. 1 is an elevational view of a knitting ball carrier showing my new design; and

Fig. 2 is another elevational view thereof rotated at an angle of 90° and illustrating the ball holder in open position.

I claim:

The ornamental design for a knitting ball carrier or similar article, substantially as shown and described.
